UNITED STATES PATENT OFFICE.

GEORGE DANIELS, OF ST. LOUIS, MISSOURI.

SIGNAL.

Application filed February 5, 1923. Serial No. 617,036.

To all whom it may concern:

Be it known that I, GEORGE DANIELS, a citizen of the United States, residing at St. Louis, in the State of Missouri, have invented a new and useful Signal, of which the following is a specification.

This invention relates to signals of the type known as monkey motion signals.

The object of the invention is to provide a signal to be located at a street crossing or any other place requiring such a device, and which includes vertically swinging semaphore-like arms or wings lever actuated and controlled by an operator to direct pedestrians and vehicle drivers as to the route to be taken.

Another object is to provide an apparatus of this character which is simple, strong and efficient and which responds quickly to the movement of the actuating lever.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a vertical section of the casing in which this signal is mounted with the signal and its cooperating parts shown in elevation.

Fig. 2 is a horizontal section taken on the line 2—2 of Fig. 1.

Fig. 3 is a similar view taken on the line 3—3 of Fig. 1.

Fig. 4 is a detail perspective view of one of the cable operating arms of the device.

Fig. 5 is a top plan view of the signal.

Fig. 6 is a horizontal section taken on the line 6—6 of Fig. 7, and

Fig. 7 is an enlarged detail vertical section of the upper portion of the signal with two of the direction indicating arms shown in elevated position.

In the embodiment illustrated, a frame 1 is shown preferably of angle iron enclosed in a casing 2 of any suitable material to protect the regulating parts of the signal.

An upright shaft 3 is mounted to rotate in the top and bottom members of the frame 1 for a purpose presently to be described.

A base plate 4 is riveted or otherwise se-

cured to the top of casing 2 over the bearing in which the shaft 3 is journaled and has a head 10 rising therefrom which includes pairs of guide arms 11 arranged diametrically opposite each other, as shown clearly in Fig. 5, four pairs of these arms being employed. The arms 12 and 13 of each pair are spaced laterally apart to form guides for the signalling wings to be described, and these arms are connected at their outer ends by transverse rods 14 which also operate as stops to limit the downward swinging movement of the direction indicating wings.

Four direction indicating wings, 15, 16, 17 and 18 are employed, those 15 and 16 being arranged diametrically opposite each other, and those 17 and 18 being arranged in transverse alignment and in planes at right angles to the wings 15 and 16 as shown clearly in Fig. 5.

The direction indicating wings are preferably made arcuate in form as shown clearly in Figs. 1 and 7 and are pivotally mounted at their inner ends between the members 12 and 13 of the guide arms 11. The body portions of these wings beyond their pivots 19, are sufficiently heavy to cause the wings to drop into lowered inoperative position when released.

Fixed to the shaft 3 inside the casing 2 and at points spaced vertically from each other are two arms 20 and 21, which extend in planes at right angles to each other as is shown clearly in Fig. 2. To free ends of these arms are secured laterally extending loops 22, the loop at one end of each arm extending in an opposite direction to that at the other end and through which are designed to pass actuating cords or cables 23 which are connected at one end to the inner ends of the direction indicating wings and at their other ends to the corners of the frame 1, so that when the shaft 3 is partially rotated, a pull will be exerted on two of the cords and thereby swing the corresponding wings into upright operative operating position as shown in Figs. 1 and 7. A turn of the shaft in the opposite direction will relieve the pressure or pull exerted on the two first mentioned arms and exert a pull on the other arms causing them to rise into upright position and the first actuated arms to drop by gravity.

Pulleys 24 depend from the inner faces of the top of the casing 2 adjacent the openings 25 in said top and a plate 4 through which

the cables 23 are designed to pass, said cables engaging the pulleys so that there will be no binding of the cables during their operation.

A pinion 26 is fixed to the shaft 3 at a point near its lower end and meshes with a rack bar 27 which is mounted to slide transversely in the frame 2, being of a length greater than the width of the casing 2 and projecting through the opposite walls thereof. One end of the rack bar 27 is housed in a casing 28 secured to the outer face of casing 2 and said rack bar has an upturned finger 29 which is designed to limit the reciprocatory movement of the bar in directions. This finger 29 in the bar is moved in one direction and engages the inner wall of casing 28 and when moved in the opposite direction engages the outer wall of said casing so that the rack bar may move a predetermined distance only.

The other projecting end of the bar 27 has a pin and slot connection with a lever 30 intermediate the ends thereof as is shown clearly in Fig. 1. This lever 30 is fulcrumed at its lower end to a bracket 31 which is secured to the outer face of the casing 2 at a point diametrically opposite the casing 28. This lever 30 is equipped at its upper end with a hand grip 32 of any suitable or desired construction.

In the use of this signal which may be located at any desired point preferably at a street crossing, the operator stands in convenient position to view the directions in which the pedestrians and drivers approach, and by shifting the lever 30 in one direction or the other will actuate the pairs of swinging wings to direct pedestrians and drivers in what direction they shall go. The inward movement of the lever 30 will move the rack bar inwardly causing the shaft 3 to rotate and exert a pull on two of the cables 23 to lift one pair of the swinging direction indicating wings while an outward movement of this lever will relieve the pull on these wings and exert a pull on the opposite pair of wings, causing them to rise into direction indicating position.

It is of course understood that any suitable protection may be provided for the operator, but as that constitutes no part of the invention such protecting means are not shown.

Various changes in the form, shape, proportion and other minor details of construc-

tion may be made without departing from the principle or sacrificing any of the advantages of the claimed invention.

I claim:—

1. In a signal of the class described, a supporting structure, a shaft mounted to rotate therein, movable indicating wings mounted on said structure, arms secured to said shaft, guides carried by said arms, cables connected at one end with said swinging members and at their other ends with said structure and passing through the guides of the arms, and means for rotating the shaft in opposite directions whereby the wings are alternately raised and lowered. 70

2. In a signal of the class described, a supporting structure, a vertical shaft mounted to rotate therein, vertically movable indicating wings mounted on said structure above said shaft, arms secured to said shaft and extending in planes at right angles to each other, guides carried by said arms, cables connected at one end with said swinging members and at their other ends with said structure and passing through the guides of the arms, and means for rotating the shaft in opposite directions, whereby the swinging wings are alternately raised and lowered. 75

3. In a signal of the class described, a supporting structure, a head mounted on the upper end of said structure and including pairs of oppositely extending guide arms, the arms of each pair being laterally spaced and connected at their outer ends, an arcuate wing pivotally mounted at one end between each pair of said arms and adapted to rest at its free end on the connection at the outer end thereof, cables connecting the pivoted ends of said wings with said structure, a shaft mounted for rotation in said structure, arms fixed to said shaft and having guides through which said cables pass, and means for rotating the shaft to exert a pull on alternate pairs of the cables for raising and lowering the swinging wings. 95 100

In testimony that I claim the foregoing as my own, I have hereto affixed my signature in the presence of two witnesses.

GEORGE DANIELS.
